UNITED STATES PATENT OFFICE.

JACOB STEPHAN, OF CLEVELAND, OHIO.

FURNITURE.

1,357,740.

Specification of Letters Patent.

Patented Nov. 2, 1920.

Application filed December 14, 1917. Serial No. 207,052.

To all whom it may concern:

Be it known that I, JACOB STEPHAN, a citizen of the United States, residing at Cleveland, in the county of Cuyahoga and State of Ohio, have invented a certain new and useful Improvement in Furniture, of which the following is a full, clear, and exact description.

This invention relates to an article of furniture capable of being used for a variety of purposes such as a davenport or settee, couch and bed. More particularly it relates to adjustable end members normally serving as arm rests, but capable of being shifted to inclined position as when used as a head rest for reading purposes, and to horizontal position in which event they will serve as extensions to convert the furniture to a full length bed and allow the occupant 20 to lie in full reclining position.

The invention more specifically considered, resides in the combination of the arm rests with the end frame members, both of which are constructed so as to enable the 25 arm rests to be turned or rolled on the former when the adjustments are being made, without affecting the ornamental appearance of the device, together with members which are constructed to accommodate 30 the different movements of the arm rests on the end frame members, and to hold the parts securely in any desired adjusted position.

The invention may be further briefly summarized as consisting in certain novel details of construction and combinations and arrangements of parts which will be described in the specification and set forth in the appended claims.

40 In the accompanying sheet of drawings wherein I have shown the preferred embodiment of my invention, Figure 1 is a perspective view of a piece of furniture equipped with my invention, the arm rests being 45 shown by full lines in normal position, and by dotted lines in two possible positions of adjustment; Figs. 2 and 3 are enlarged sectional views showing how the arm rests are supported in different positions and can be 50 turned or rolled on the end frame members, and Fig. 4 is a fragmentary inside view of the same.

The furniture constituting the subject matter of this invention is ordinarily used 55 as a settee, davenport, or ornamental seat for two or more persons, and it includes

preferably a rectangular box-like frame 10, at the top of which is upholstery 11, normally constituting a cushioned seat, and adapted also to serve as a mattress in the 60 event the device is used as a bed. The frame 10 preferably forms a receptacle for mattress and spring sections, such as disclosed in my prior application, Serial No. 53,164, filed September 29, 1915, and which can be 5 slid out from the frame so as to form an extension bed precisely as in the manner explained in my prior application.

Above the ends 10^a of the frame are what are normally arm rests 12, which ordinarily 70 stand in upright position on the end frame members 10^a, but are designed to be swung to or supported in inclined position indicated at 12^a at the left hand side of Fig. 1, so as to serve as a head-rest, and to horizontal position, indicated at 12^b at the right hand side of Fig. 1. Either arm rest can be swung to inclined position, or to a horizontal position, and when in the latter position the device can be used as a full length 80 bed, in which event the upholstered parts 13^a of the arm rest form substantial continuations of the upholstery or seat 11.

In order that the arm rests may be swung to, and supported in the several positions 85 stated, or other intermediate positions if desired, and in order that at the same time the furniture may have an attractive ornamental appearance, the parts 10^a and 12 are 90 connected together, and the parts 12 are adapted to be supported and to turn or roll on the parts 10^a in the manner which will now be described. It will be observed that at the upper marginal edges of the end frame members 10^a, concave rounded grooves 95 10^b are provided, and at the lower outer marginal edges of the arm rests 12, rounded heels or beads 13^a are provided for a purpose to be subsequently explained.

Heretofore in somewhat similar pieces of 100 combination furniture with adjustable arm rests, complicated and rather unsightly supporting devices, generally consisting of links and braces have been employed. I 105 avoid such devices and employ hinges which are practically at all times, and have practically all their portions concealed from view. The hinges, two of which are preferably employed for each arm rest, include 110 leavess 14 which are rigidly secured to the arm rests 12, and preferably extend under the upholstery 13^a, as shown in Figs. 2 and 3.

The hinges include also, hinge leaves 15, which extend downward from hinge pins or pintles 16 along the inner sides of the end frame members 10^a, and are normally 5 wholly covered by the upholstery 11. Additionally for each lower hinge leaf 15 I employ an anchor plate 17 which is secured by screws or equivalent fastening means to the inner side of the corresponding end 10 frame member 10^a in such position that the lower hinge leaf 15 will bear against the same.

Each lower hinge leaf 15 is provided with a long slot 18 having enlarged portions 19, 15 preferably circular in form, the number and spacing of which will depend upon the number of positions in which the arm rests are adapted to be supported. Generally in addition to the upright position, two additional 20 positions are all that are necessary, the latter including the horizontal and one inclined position which may be, and preferably is, about midway between the upright and horizontal positions. These enlarged 25 portions 19 of the slot 18 of each hinge member 15 are adapted to receive or hook onto a boss 17^a, preferably circular in form, of the associated anchor plate 17, as clearly shown in Fig. 2.

30 Additionally the fastening means between the two parts 10^a and 12 preferably include thumb screws 20 which screw into the anchor plates centrally with respect to the bosses 17^a of the latter, and hold the hinge members 15 down against the anchor plates.

It will be observed that the anchor plates have a slight convex curvature, and that the lower leaves or hinge members 15 also have a slight curvature extending substantially 40 from the pintles 16 to substantially the lower ends of the hinge members 15. The curvatures in these members is for the purpose of enabling the hinge members 15 and the anchor plates to lie or bear squarely 45 against one another when the arm rests are in the various positions to which they may be moved.

Ordinarily each arm rest is supported on the corresponding end frame member 10^a in 50 the manner shown in Fig. 2, with the boss of each anchor plate in the upper enlargement of the slot 18 of the associated lower hinge member. The parts are held in these 55 positions with the lower hinge member lying squarely against the slightly curved anchor plate by means of the thumbscrew 20. To shift either arm rest from the full line position of Fig. 1 to either dotted line position shown in the same figure, the thumb- 60 screws are loosened, the lower hinge members 15 are moved outwardly slightly so as to clear the bosses of the anchor plates, and then the arm rest is swung to the desired position and the appropriate slot enlargements 65 19 are engaged or hooked over the

70 lugs of the anchor plates and the thumbscrews are again tightened. When this adjustment of the arm rest is made, the curved heel or bead 13^d of the arm rest engages and rolls in the groove 10^b on the upper outer marginal edge of the end frame member so that the latter constitutes a fulcrum which not only permits the turning movement to take place, but serves as an important part 75 of the supporting means for the arm rest. In fact, by reason of this rolling action I can employ simple hinges without any additional bracing devices, but nevertheless, the members 12 will be amply supported or secured. Additionally by reason of this construction, the outer appearance of the ends of the furniture is not marred even though the ends are sectional and composed of relatively movable parts, but on the other hand, the appearance is pleasing, the joint or line 80 of separation viewed from the end of the furniture being ornamental rather than otherwise.

Having described my invention, what I 90 claim is:

1. An article of furniture comprising a frame adapted to constitute a seat and having an arm rest normally supported in upright position on the end of the frame, hinge members on the inner side of the arm rest 95 and end frame member, one hinge member being secured to one part, and the co-operating hinge member being adjustably secured to the other part so that the arm rest can be swung relative to the end frame member, 100 the outer adjacent edges of the arm rest and end frame member having portions shaped to permit the arm rest to turn or roll on the end frame member.

2. An article of furniture comprising a 105 frame adapted to constitute a seat and having an arm rest normally supported in upright position on the end of the frame, hinge members on the inner side of the arm rest and end frame member, one hinge member being secured to one part, and the co-operating hinge member being adjustably secured to the other part so that the arm rest can be 110 swung relative to the end frame member, the outer adjacent portions of the end frame member and arm rest having one a groove 115 and the other a heel which is received in and turns in the groove when the arm rest is being turned from upright, toward or from horizontal position.

3. An article of furniture comprising a frame with end members, arm rests carried thereby and resting on the end members, means connecting the arm rests to the end members so that each arm rest may be adjusted and firmly held in adjusted positions, said means including a member secured to the inner part of the arm rest and adjustably secured to the inner part of the end member, each arm rest and the associated end mem- 130

ber having portions shaped to permit the arm rest to have a rolling action on the end member when the arm rest is being adjusted.

4. An article of furniture comprising a frame with end members, arm rests carried thereby and resting on the end members, means connecting the arm rests to the end members so that each arm rest may be adjusted and firmly held in adjusted positions, 5 said means including hinges composed of leaves secured to the inner lower part of the arm rest, and hinges pivotally connected to the first named, and adjustably secured to the inner upper part of the end member, and 10 15 said end members having anchor plates and securing means by which the lower hinge members can be secured to the anchor plates, each arm rest and the associated end member having portions shaped to permit the 20 arm rest to have a rolling action on the end member when the arm rest is being adjusted.

5. An article of furniture comprising a frame with end members, arm rests carried thereby and resting on the end members, 25 means connecting the arm rests to the end members so that each arm rest may be adjusted and firmly held in adjusted positions, said means including hinges composed of leaves secured to the inner lower part of each 30 arm rest, and leaves pivotally connected to the first named, and adjustably secured to the inner upper part of the end member, and said end members having anchor plates and securing means by which the lower hinge 35 members can be adjustably secured to the anchor plates, the anchor plates and lower hinge members having correspondingly curved engaging surfaces, each arm rest and the associated end member having portions 40 shaped to permit the arm rest to have a rolling action on the end member when the arm rest is being adjusted.

6. An article of furniture comprising a frame adapted to constitute a seat, and having an arm rest supported on the end of the frame and adjustable thereon to different positions, the adjacent portions of the arm rest and end frame member being shaped to permit the arm rest to have a rolling action on the end frame member when the arm rest 45 is being swung from one position to another, and means for securing the arm rest to the end frame member comprising a member connected to the inner portion of one part and adjustably secured to the inner portion 50 of the other part.

7. An article of furniture comprising a frame adapted to constitute a seat and having an arm rest supported on the end thereof and adjustable thereon to different positions, 60 the lower portion of the arm rest being supported on the end of the frame and having a rolling action on the latter during adjustment, and means for securing the arm rest to the frame and for supporting the arm 65 rest in any of its adjusted positions comprising a tension member connected to one part and adjustably secured to the other part.

8. An article of furniture comprising a frame adapted to constitute a seat and having an arm rest supported on the end thereof and adjustable thereon to different positions, the lower portion of the arm rest being supported on the end of the frame and having a rolling action on the latter during adjustment, 70 and means for securing the arm rest to the frame comprising a supporting member extending between the arm rest and frame inside of the engaging portions thereof.

In testimony whereof, I hereunto affix my signature.

JACOB STEPHAN.
